UNITED STATES PATENT OFFICE.

MAREK PIEROG, OF NEW ABERDEEN, NOVA SCOTIA, CANADA.

ANTISUBMARINE DEVICE.

1,299,775.

Specification of Letters Patent. Patented Apr. 8, 1919.

Application filed July 2, 1918. Serial No. 242,997.

To all whom it may concern:

Be it known that I, MAREK PIEROG, a subject of the Emperor of Austria; residing at New Aberdeen, Province of Nova Scotia and Dominion of Canada, have invented 5 certain new and useful Improvements in Antisubmarine Devices, of which the following is a specification.

This invention relates to improvements 10 in devices for fending or warding off the attacks of undersea projectiles.

The principal object of the invention is to provide a novel form of net adapted to be disposed circumjacent to the hull of a vessel, the net being comprised of relatively small sections interengaged together, and so constructed as to offer a resilient armor effectually preventing damage from occurring by the attack of a torpedo, mine or like undersea projectile.

A further object is to provide support means for the net in which the distance between the net and the hull of the vessel may be varied.

These and other like objects are attained by the novel construction and combination of parts hereinafter described and shown in the accompanying drawings, forming a material part of this disclosure, and in 25 which:

Figure 1 is a top plan view showing a conventional type of ship and indicating the application of the invention.

Fig. 2 is an enlarged fragmentary vertical sectional view of the net, showing the manner of attachment to the ship.

Fig. 3 is a similar view of the same showing the parts in their relative positions during the rolling motion of the vessel.

Fig. 4 is an enlarged fragmentary side elevational view of the net, and

Fig. 5 is a greatly enlarged sectional view taken on line 5—5 of Fig. 2.

Referring now more particularly to the drawings, the numeral 10 indicates a conventional type of a ship having all the usual mechanisms for navigation and propulsion.

Attached at uniformly spaced intervals, at the upper portion of the hull of the ship, 50 are support bars 14, preferably rigidly affixed within the hull by screws or rivets 15, the outer downturned ends 16 of the support bars being formed into hook-like elements 17, engageable with eyes 18, secured in the upper horizontal elements 19 of the warding net frame 20. A similar base ele-

ment 21 extends outwardly in the manner of a ledge or flange from the lower edge of the frame 20, while interposed therebetween are horizontal plates 22 extending outward to 60 the same distance as the upper and lower plates 19 and 21.

Extending between these several plates 19, 21 and 22 are vertical strips 24 forming a plurality of cells 25, adapted to receive and firmly maintain a similar number of coiled springs 26, the same being made of resilient wire and adapted to interpose an effectual barrier between the advancing 65 point of an undersea projectile and the hull 70 of the ship, forming in effect a substantially invulnerable guard.

Attached to the hull of the ship are brackets 30, the same being engaged by means of bolts or rivets 31 and formed with cylindrical extensions 32 engageable within similar cylinders 33 having enlarged outer heads 35 and connected with the fixed cylinders, upon which they are slidable by pins 36 the amount of movement being controlled by 80 slots 37 in which the pins move.

Affixed in the outer ends of the heads 35 are rotatably mounted wheels 39, the same being adapted to engage with the rear of the vertical chambers and rigidly secured in the frames 20 are bars 40 enterable within appropriate openings formed in the head 35, the inner ends of the bars being formed into racks 41 engageable with the gears 42 fixed on spindles 44, rotatably mounted in the 85 cylinders 33.

Also fixed on the spindles 44 so as to rotate with them, are bevel gears 45, meshing with mating gears 46, secured on the ends 90 of sleeves 48, rotatably mounted in the bearings 49, secured to the cylinder 33 so as to move longitudinally of the cylinder 32.

The interior of the sleeves 48 are screw-threaded and engageable with the threaded ends 50 of rods 51, secured by brackets 52 100 within the main brackets 30, attached to the hull of the vessel, thus providing a supporting means, which at the same time will permit of the swaying or lateral movement of the net relative to the hull of the ship as 105 can be seen in Figs. 2 and 3.

In operation if the ship is caused to sway, obviously the racks tends to move away from their supports which movement actuates the train of gears and their operative 110 connections so that the head 35 may be moved to or from the hull of the ship in an

obvious manner, thereby permitting the net to remain substantially vertical at all times.

Having thus described my invention what I claim as new and desire to secure by Letters Patent, is.

- 5 1. In a net support, the combination with a bracket secured to the hull of a ship, said bracket having an outwardly extending horizontal cylinder, a second cylinder engaged telescopically on the first named cylinder, a head formed with said second cylinder, a net having a rigid backing, a rack extending from said backing into the head of the second named cylinder, a spindle mounted transversely in said second cylinder, a gear on said spindle engageable with the teeth of said rack, a threaded sleeve carried by one of said cylinders means combined with said gear for rotating said

threaded sleeve, and a screw threaded bolt 20 fixed within the lower end of said bracket engageable within said threaded sleeve whereby, due to the movement of said net, said cylinders are moved one within the other.

- 25 2. In a net support, the combination with a pair of telescopic elements one being rigidly engaged upon the hull of the ship, and the other slidably thereon, of a head formed with the second named telescopic elements, 30 a rack bar enterable through said head, said rack bar being engaged with a net, and means operable by said rack bar whereby the second named telescopic element is moved upon said rigid element.

35 In testimony whereof I have affixed my signature.

MAREK PIEROG.
